UNITED STATES PATENT OFFICE

1,927,501

MACHINE FOR ROLLING SHEET METAL SHAPES

Albert Rafter, Belleville, N. J., assignor to Rafter Machine Company, Belleville, N. J., a partnership composed of Albert Rafter and John C. Rafter, Jr.

Application February 2, 1932. Serial No. 590,355

1 Claim. (Cl. 153—28)

This invention relates to rolling machines for forming strips of cold sheet metal into desired shapes, and more particularly to a roll speed equalizer for controlling the speed of the strips 5 of metal as they pass through the machine.

A machine of the type herein considered is described in U. S. Patent No. 1,792,122, issued to me on February 10, 1931. Such machines have a plurality of pairs of cooperating upper and 10 lower die rolls. A strip of cold metal is passed between one pair of die rolls to the following pair, the die rolls being progressively shaped to gradually form the sheet metal strip into the desired shape. The lower die rolls are substantially 15 of the same diameter, but the upper die rolls gradually increase in diameter, and consequently the peripheral speed of the upper die rolls increases as the metal progresses through the machine, and all of the rolls are rotated at the same speed. 20 The variation in the peripheral speeds of the upper die rolls is objectionable in that the various portions of the metal strip are urged to move at different speeds resulting in buckling and bending of the sheet metal strip. Also, the upper die rolls slip over the metal, the slipping increasing as the diameters of the die rolls increase, resulting in an undesired, an uneven, wearing of the die rolls which causes improper forming of the 25 metal sheets. Inasmuch as die rolls are expensive and must be carefully and accurately made, it is essential that uneven wearing of the die rolls be eliminated. Heretofore, this has been accomplished by providing gearing designed to 30 drive the various die rolls at different and proper speeds; that is, to cause the peripheral speeds of all of the die rolls to be substantially the same so that there will be no slipping or sliding of the metal sheet as it passes between the rolls. 35 But as is obvious, gearing to produce the proper speeds for a given set of die rolls will be ineffective for another set of rolls; and consequently the equalizing of peripheral speeds by especially designed gearing is objectionable in that whenever 40 it is desired to form the metal into a different shape it is necessary to rearrange the gearing. Such a procedure is very expensive and inconvenient, and inasmuch as many manufacturers desire to use the same machine for making several different shapes, it is desirable that a machine be provided which is universal in its 45 application.

It is, therefore, an object of this invention to provide a metal forming machine having a plurality of pairs of die rolls, all of which rolls have

substantially the same peripheral speed regardless of the diameters of the rolls.

A further object is the provision, in a metal forming machine, of friction clutch means interposed between each die roll and the means for driving the roll, so that any undue force on the die roll due to difference in speed between the die roll and the metal sheet passing between the die rolls will cause the driving means to be automatically disconnected from the die roll.

These and other advantageous objects, which will later appear, are accomplished by the simple and practical construction and arrangement of parts hereinafter described and exhibited in the accompanying drawing, forming part hereof, and in which:

Figure 1 is a fragmentary elevational view of a cold metal forming machine having a plurality of pairs of die rolls.

Figure 2 is a view, partly in section, of a pair of die rolls and the driving means therefor embodying my invention.

Figure 3 is a side elevational view taken on line 3—3 of Figure 2.

Figure 4 is a perspective view of frictional clutch members employed in the form shown in Figure 2.

Figure 5 is a partly sectional view of a pair of die rolls and the driving means therefor, employing a modified form of friction clutch, and

Figure 6 is a perspective view of a conical element of the frictional clutch shown in Figure 5.

Referring to the drawing, a cold metal forming machine is shown in Figure 1 to have a plurality of pairs of die rolls; the lower rolls 7 of each pair being of the same diameter, while the upper rolls 8, 9, 10, 11, 12 are respectively of gradually increasing diameters. All metal forming machines of the type herein described have a plurality of pairs of die rolls, and while in Figure 1, the machine is shown to have but five pairs of die rolls, it is to be understood that in some instances these machines may have ten, or more pairs of die rolls.

In Figure 2 is shown the general arrangement of a pair of die rolls 7 and 12, which are used, for example, to form a strip of cold metal into a channel 30. The upper die roll 12 is fixed to a shaft 19, and the lower roll 7 is fixed to a shaft 20, the shaft 19 being journaled in bearings 14, 16 and 18 respectively in the housings 13, 31, and 17 respectively, while the lower shaft is journaled in a bearing 15 in housing 13 and in similar bearings in housings 31, 17. Shafts 19 and 20 are rotated at the same angular speed by

means of driving means (not shown) engaging the gears 22, 21, which gears in turn are in mesh with pinions 23, 24, the latter being in mesh with gears similar to the gears 22, 21 on the next succeeding die roll unit, so that all of the die rolls on the machine are rotated substantially at the same angular speed. The lower die rolls 7 of the machine, being of the same diameter, consequently have the same peripheral speed. But the upper die rolls 8, 9, 10, 11 and 12 being of different diameters, naturally have different peripheral speeds; and the difference in the peripheral speeds is compensated for by means hereinafter described.

15 The driven gear 22 on upper shaft 19 is shown in Figure 2, to be loosely mounted and to have an inwardly projecting centrally positioned annular flange 22' which is in frictional engagement with the flanges 28, 29, of the collars 28', 29', (see Fig. 4) the collars being on opposite sides of the flange 22' and splined to the shaft 19. A compression spring 27 bears against flange 28 and urges the latter constantly into engagement with the annular flange 22', the flange 29 of collar 29' being restricted in movement in one direction by contact with the bearing 16.

16 The shaft 19 is threaded at 25 and carries a threaded nut 26 which engages the spring 27 and serves as means for adjusting the tension of the spring.

17 In operation, when resistance is encountered by the roll 12 due to the difference in peripheral speeds of rolls 7 and 12, and a metal strip passing through the machine, flange 22' slips over the flanges 28, 29 against the pressure of spring 27, so that while gear 22 will be rotated at a constant speed, the rotary speed of shaft 19 and die roll 12 will be varied to cause equalization of the peripheral speeds of die rolls 7 and 12.

18 While a specific form of friction clutch is shown in Figure 2, it is obvious that the friction clutch may be made in a number of forms without departing from the spirit of my invention. For example, in Figure 5, is shown a form of friction clutch in which a driven gear 40 has an annular wedge-shaped flange 41 which is engaged on opposite sides by conical members 42, (see Fig. 6) which are splined to shaft 19, the conical members corresponding to the collars 28', 29' and flanges 28, 29 shown in Figures 2 and 4, and are

19 maintained in contact with wedge-shaped flange 41 by compression spring 27 as above described.

20 Obviously, it is not essential that the friction clutch members be located in connection with the driven gears as shown in Figures 2 and 5, but may be placed any place between the driving means and the die roll and accomplish substantially the same result. For example, the friction clutch means may be associated directly with the die roll itself; the essential feature being the provision of friction clutch means interposed between the driving means and the die roll to compensate for abnormal resistance on the upper die roll due to the difference between the peripheral speed of the die roll and the speed of the strip of metal passing between the upper and lower rolls. It is also clear that the friction means may be applied to the lower die roll as well as to the upper die roll and produce the same result, without departing from the spirit of the invention.

21 From the above description it will be seen that I have provided effective means for equalizing the speeds of the die rolls of a cold metal forming machine, which means are the same regardless of the die rolls used, and which require no change of gearing or other parts when it is desired to form different shapes on the same machine.

22 The foregoing disclosure is to be regarded as descriptive and illustrative only, and not as restrictive or limitative of the invention, of which 105 obviously an embodiment may be constructed including many modifications without departing from the general scope herein indicated and denoted in the appended claim.

23 Having thus described my invention, what I 110 claim as new and desire to secure by Letters Patent, is:

24 In a machine for forming cold metal into desired shapes, an upper shaft and a lower shaft, 115 die rolls of different diameters mounted on said shafts, gears to drive the shafts, means to rotate the gears at the same angular speed, the gear on the upper shaft having an inwardly projecting annular flange, a collar attached to the upper shaft and frictionally engaging one side of the flange, 120 a second collar splined to the upper shaft, and resilient means normally urging said second collar into frictional engagement with the other side of the flange.
